(57) **CLAIM**

The ornamental design for a mounting bracket for manifold assembly, as shown and described.

DESCRIPTION

FIG. 1 is a perspective view of a mounting bracket for manifold assembly showing our new design;

FIG. 2 is a top plan view thereof;

FIG. 3 is a right side elevational view thereof;

FIG. 4 is another perspective view thereof that is identical to FIG. 1, except that the depiction in broken lines of unclaimed environmental structure has been omitted;

FIG. 5 is another top plan view thereof that is identical to FIG. 2, except that the depiction in broken lines of unclaimed environmental structure has been omitted; and, FIG. 6 is another right side elevational view thereof that is identical to FIG. 3, except that the depiction in broken lines of unclaimed environmental structure has been omitted. The broken lines in FIGS. 1-3 form no part of the claimed design.
